UNITED STATES PATENT OFFICE.

FRANK A. LUNDQUIST, OF CHICAGO, ILLINOIS.

CALLING DEVICE FOR TELEPHONE-EXCHANGES.

No. 846,327.

Specification of Letters Patent.

Patented March 5, 1907.

Application filed June 13, 1904. Serial No. 212,325.

To all whom it may concern.

Be it known that I, FRANK A. LUNDQUIST, a citizen of the United States of America, and a resident of Chicago, county of Cook, and State of Illinois, have invented certain new and useful Improvements in Calling Devices for Telephone-Exchanges, of which the following is a specification.

My invention relates to calling devices for telephone-exchanges, and has for its object improvement in the construction and operation of such devices.

In the accompanying drawings, Figure 1 is an elevation of the device. Fig. 2 is an enlarged elevation with the front cover removed and showing the parts in their normal position. Fig. 3 is a similar elevation showing the parts as they appear while operating to make a call. Fig. 4 is an elevation similar to Fig. 2, partly in section and with the front parts removed, so as to show the interior mechanism. Fig. 5 is a detail in side elevation of some of the contact-making parts of Figs. 2 and 3. Figs. 6 and 7 are sections on lines 6 and 7, respectively, of Fig. 5. Fig. 8 is a condensed and simplified diagram of central-office mechanism adapted to be used in connection with the calling device, and Fig. 9 is a diagram representing a series of local stations on two party-lines running from the central office.

In the said drawings, C is a box upon the front face of which is a numbered and rotatable dial D, mounted upon a spindle D', to which it is secured. A spring D² normally holds the dial with its zero-point adjacent to an indicating-pointer D³. This normal position is determined by a pin E' on the spindle E, which spindle is connected to the spindle D' by a train of gears, as shown in Fig. 4.

In its normal position the pin E' rests between and is held stationary by the pivoted levers E² and E³. The lever E³ is normally held in the position shown in Fig. 4 by a spring E⁴. The lever E² has no such spring, but rests at the place at which it is put until moved to a different position.

The large gear D⁴ is connected to the spindle D' by a ratchet mechanism (not shown) which permits the spindle to be turned in one direction without turning the gear, but which drives the gear when turned in the opposite direction.

A hand-wheel D⁵ is the means by which the spindle D' and the disk or dial D are turned by hand in the direction of the arrow

in Fig. 1 without moving the gear D⁴, which forms part of the train of gearing between spindles D' and E. In doing this the levers E² and E³ do not release the pin E' until a further operation. Consequently the dial may be set by hand for any indication, and it will remain at this place until it is desired to have it move. The lever E² extends through a slot C' of the plate C², which forms part of the frame that holds the mechanism. On the spindle D' is an arm D⁶, which when the spindle is in its normal position strikes the lever E² and holds its lower end in the path of the pin E'. On the other end of the lever E² is a piece of insulation E¹⁰, which when the lever is held in its normal position by the arm D⁶ strikes spring 25 and closes it to contact with spring 26.

Pivoted at a convenient place on the plate C² is a lever F, which is normally held in an elevated position by spring F'. On the lever F is a spring F², which engages the end of lever E² to move it away from springs 25 and 26 and from the pin E' when the arm D⁶ has been moved from its normal position, as shown in Fig. 3. If the arm is in the position shown in Fig. 2, then a depression of the lever F would only cause the spring F² to yield without moving lever E².

Assuming the dial D to have been set at any indication and the arm D⁶ moved away from lever E², then a depression of the lever F will release the pin E', and the said pin will move away from the end of lever E³. This motion is by virtue of the spring D², operating through the train of gears upon the spindle E. As the pin E' approaches the lever E³ from the other side it pushes said lever outward, so that it can pass. Secured to the lever E³ is a disk E⁵, having a notch E⁶. Pivoted at a convenient point is a lever E⁷, adapted to engage the notch E⁶, so as to hold the lever E³ clear of the pin E'. A spring E⁸ furnishes the force for this holding action. Secured at some convenient place on the spindle D' is an arm the end of which is indicated by dotted lines at E⁹ in Fig. 4. When the spindle D' is at its normal position, the arm E⁹ strikes the lever E⁷ and moves it away from the notch E⁶; but as soon as the spindle has been advanced the spring E⁸ will throw the lever E⁷ into position to engage notch E⁶ as soon as pin E' has moved lever E³ outward.

The general construction and operation so far described is that the dial D may be set at

any indication desired and will remain at that place until released by a pressure on the lever or key F. When this release occurs, the dial runs back to its normal position, 5 where it stops and is locked. This stopping and locking is primarily effected by the arm D⁶ pushing the lever E² into the path of the pin E' and secondarily by the arm E⁹ releasing the lever E⁷, so that the spring E⁴ 10 may force the end of lever E³ behind the pin E'. This last action prevents a rebound of the mechanism when suddenly stopped.

On the spindle E is a ratchet-wheel E¹¹, which is connected by means of a pawl with a 15 governing device E¹². These parts are so arranged that when the spindle is driven forward by spring D² the ratchet-wheel drives the governor, and the governor acts to regulate the speed of rotation. When the spindle E is suddenly stopped by pin E' and lever E², the pawl of the governor rides over the teeth of the ratchet-wheel until stopped by friction. By this means the governor is not 20 instantly stopped, and the pin E' is relieved 25 of a corresponding amount of impact; otherwise the governing mechanism is of a well-known form. Also secured on the spindle E' is a cam 4, and supported at a convenient point is a contact-spring 3. These parts are 30 so related to each other that the cam makes an electrical contact with the spring 3 for each rotation of the spindle E. In its normal position the cam is not in contact with the spring 3. The train of gearing between 35 spindles D' and E is so related to the numbering on the dial D that the cam 4 makes one electrical contact with the spring 3 for each time the dial moves a distance equal to that between one graduation and the next.

40 The receiver-hook H is pivoted on a shaft H³ and when not depressed by the weight of the receiver R is held in an elevated position by a spring H'. Also on the shaft is segment of a gear H⁴, which is moved downward by a 45 spring H⁵, which has one end attached to the segment H⁴ and the other end to a projection on the hook H. On the hook H is a pin H², that projects into a slot H⁶ in the segment H⁴. The spring H⁵ normally holds H and H⁴ in 50 the relative position shown in the drawings; but if the segment be restrained from movement when the hook is in its elevated position then the hook may be moved downward while the segment remains stationary 55 or moves downward at a slower speed. In such a case the pin H² travels in the slot H⁶.

On a stud J is a gear J' and three cam-shaped projections J², J³, and J⁴. These parts are all fastened together, and in the 60 diagram Fig. 9 the cams are condensed into one and designated by the numeral 21. The gear J' meshes with the segment H⁴ and by suitable gearing and ratchet-wheel is connected with an escapement J⁷. The object 65 of these parts is to regulate the speed of the

downward movement of the segment H⁴, while not restricting its upward movement.

Supported at a convenient place are five insulated contact-springs which make and break electrical connection with the cam-surfaces that turn on the stud J. When the hook H is at its lowest position, connection is to the spring 20, the other springs being out of electrical connection. When the hook H is at its highest position, the connection is to 75 springs 28 and 40. When the hook is passing between its extreme positions, the connection is to springs 30 and 31.

Secured to the plate C² is a lever L, having three arms or projections. One of these, L', 80 is insulated and normally rests adjacent to but separated from a contact I. A second one of these arms rests adjacent to a pin F³ on the lever F. The third arm projects adjacent to a pin J⁶, which is carried by the 85 cam-body that turns on stud J. When the hook H is in its lowest position, the pin J⁶ engages the lever L and moves the part L' out of connection with the contact I. When the hook rises, the pin J⁶ moves away and leaves 90 L in condition to be moved by depressing lever F, thus bringing L' into contact with I. The lever L stays in the place it is put until moved by either pin J⁶ or by pin F³ on lever F. Connection between L' and I throws the 95 battery-line to springs 3 and 30, through either of which impulses are sent by the movement of their adjacent cam-surfaces.

Upon removing the receiver R from its hook the said hook rises and rotates the cam-surfaces on stud J (21 of Fig. 9) and makes and breaks connections with the adjacent springs. As there is no battery connection until the lever F has been moved and this movement is not made until after the receiver is removed, these contacts are without effect. Upon the descent of the hook, however, this is different, because ordinarily the lever F has been previously moved. The contacts made with springs 30 and 31 during 100 the intermediate part of the hook movement are used to send impulses for releasing the switching mechanism at the central office. The escape mechanism is used to prevent these contacts from being made so quickly as 105 to be ineffective. If the hook H were rigidly connected to the segment H⁴, then a sudden or forced descent of the hook would be liable to break or damage the escapement. By making a yielding connection between the 110 two the hook may be forced down suddenly without causing the segment H⁴ to move any faster than the spring H⁵ will carry it against the resistance of the escapement.

It will be observed that electrical contacts 115 are made by the movement of the receiver-hook, but that they are made through an intermediary and not directly. It will also be observed that the speed of these contacts is independent of the speed of the hook. The 120

particular devices illustrated for this purpose are divided or yielding connections between the hook and the actual contact-makers. The results obtained are a definite speed of 5 contact-making and immunity from breakage or damage by accident or careless handling of the hook.

The calling device here illustrated is particularly well adapted for use in exchanges 10 which combine party-line systems with automatic exchanges. For the sake of simplicity in drawings and description, however, I have chosen to illustrate it as connected to the kind of exchange shown in my Patent No. 15 606,764, issued July 5, 1898. In doing this I have omitted in the central-office apparatus all parts and connections not necessary to an understanding of the general operation. The central-office apparatus consists of a switching 20 mechanism for each line running out of the office and a battery and battery-strip common for all switching mechanism. The switching mechanism is of the kind shown in my said patent, and consists of a contact-maker P, that is moved into connection with any one of a series of contact-points, and hence through suitable connections to connection with any other switching mechanism. The magnet A is used for advancing the contact-maker P, and the magnet B is used for releasing the mechanism, so that it may return to its normal position. One or more local stations may be on each line that extends from the central office. When there 25 are two or more stations on a line, there will be additional apparatus at the central office, as shown in my previously-mentioned application; but as such additional apparatus is no part of the present application it is omitted.

30 Assuming that the subscriber at station No. 11 on the line from switch No. 1 wishes to call the subscriber at station No. 22 on the line from switch No. 2, he would proceed as follows: If there is more than one station on his line, he will remove his receiver and listen to see if the line is busy. If it is busy, he restores his receiver and waits. If it is not busy or if there is no other station on his line, he sets his dial D at "2," presses the key or 35 lever F, and as soon as the dial returns to normal position he gives two rings with his generator. When through talking, he hangs up his receiver. The setting of the dial and the number of rings is a reading from the station-number in the system chosen for illustration. Any system of numbering may be used. When the dial is set at "2," it stays at that place until the key F is pressed. This gives the subscriber ample opportunity to observe 40 his setting before he makes a call and tends to obviate errors. Pressing key F releases E² from pin E' and permits cam 4 to rotate and make two contacts with spring 3 before arm D² strikes lever E² and moves it to stop pin E'. Each time such a contact is made an

impulse flows from the battery X at central through ground to station No. 11, 1 L' 2 3 4 5 6 7 A 8 9 X. This moves the contact-maker P of switch No. 1 to the second contact, which connects to switch No. 2. Operating generator sends a ringing current as follows: G at station No. 11, 10 11 12 13 14 15 16 P 17 18, to switch No. 2, 19 16 15 14 13 12 11 Q 20 21 H⁴ 6 7 A 8 9, to switch No. 1, 8 A 7 6 5 G. This ringing-circuit also goes through the 75 other stations on the same line with station No. 22; but as two rings is assumed as the signal for that station other subscribers do not respond. Beginning at station No. 11, the talking-circuit is as follows: R K 22 11 80 12 13 14 15 16 P 17 18 19 16 15 14 13 12 11 22 K 23 R 24 25 26 27 28 21 H⁴ 6 7 A 8 9, to switch No. 1, 8 A 7 6 H⁴ 21 28 27 26 25 R. When the receiver-hook at the calling-station descends, the mass 21 closes connection 85 between springs 30 and 31, when a current flows X through ground to station No. 11, 1 L' 2 29 30 21 H⁴ 6 7 A 8 9 X. This closes spring 33 to spring 34 while 31 is in contact with 21, when a branch of the above current 90 flows from 21 31 32 11 12 33 34 B 35 9 X. This releases the switching mechanism and permits it to return to its normal position. It will be observed that this circuit for release passes through L' and that this circuit 95 is open unless the key F has been depressed in making a call. It thus happens that although the release is accomplished by the descent of the hook such descent is not effective to produce release unless a call has been made. 100 This is to avoid confusion and trouble when there are several stations on one line. For example, if when the subscriber takes off his receiver he finds the line busy it would not do for him to release the switching mechanism 105 by hanging up his receiver, because such action would cut out the talking parties. The key F when operated serves as a means for making a call and when not operated serves as a means for permitting the subscriber 110 to remove and replace his receiver without interfering with a busy line.

What I claim is—

1. The combination with a receiver-hook arranged to be depressed by the weight of a receiver, and a contact-making device arranged to be operated each time that the hook is depressed, of a spring-actuated member by which said contact-making device is operated, a governor mechanism by which the speed of said member is controlled, and a slipping connection between said member and said hook, said connection being so arranged that the hook may be depressed at a greater speed than the movement of said 120 member.

2. The combination with a receiver-hook, and an arm movable with respect to each other, of a spring arranged to hold the hook and the arm normally at one extreme of their 125

movement with respect to each other, and a contact-making device operated by the movement of the arm when the hook is moving in a direction which would disturb the normal relationship between the hook and the arm if the arm remained stationary.

3. The combination with a receiver-hook, an arm, and a slotted connection between the hook and the arm, said connection being arranged to permit a limited movement of the arm and hook with respect to each other, of a spring normally holding the two at one extreme of their movement with respect to each other, and a contact-making device operated by the force of said spring when said hook is being depressed.

4. The combination with a contact-making device, and a source of power for operating it, of a receiver-hook, means by which an ascent of said hook will set said device preliminary to the making of a contact thereby, and means by which a descent of said hook will release said device.

5. In a calling device arranged to control the operations of a switching mechanism, an indicator adapted to be set for a required advance of such switching mechanism; a contact-making device arranged to send impulses for causing such advance, a spring placed under tension by the setting of said indicator and arranged to operate said contact-making device, a key for setting said device into operation so as to send the required impulses and to return the indicator to its normal position, a second contact-making device and a receiver-hook connected together, and means by which a descent of the hook will cause the second device to send an impulse to the switching mechanism over a different course than that traversed by the impulses before mentioned.

6. The combination with two courses over which impulses may be sent, of a contact-making device for sending and an indicator for determining the number of impulses to be sent over one of said courses, a second contact-making device and a receiver-hook for causing the second device to send an impulse over the second course, and an independent governor for each device for controlling the speed of its movement.

7. The combination with two courses over which impulses may be sent, of a separate contact-maker for each course, an indicator arranged to be set by hand for the sending of a desired number of impulses over one of said courses, a governor for controlling the speed with which such impulses are sent, a receiver-hook arranged so that by its descent it will cause an impulse to be sent over the second course, and means by which a forced descent of said hook is prevented from influencing the duration of the impulse over the second course.

8. The combination with a receiver-hook, and a contact device arranged to close one electrical connection when the hook is elevated, to close a second electrical connection when the hook is depressed, and to temporarily close an intermediate electrical connection while passing from the elevated to the depressed position, of means by which a rapid downward movement of the hook is prevented from affecting the rate of speed at which said electrical connections succeed each other.

9. A contact-closing device, a spring for operating it, a governor for controlling the speed thereof, means for stopping the contact-closing device when it has made the desired number of contacts, and a slipping connection between said contact-closing device and said governor whereby the impact due to stopping said closing device is reduced.

10. In a calling device, an indicator adapted to be set for the making of any desired number of contacts, a key for starting the making of such contacts into operation a circuit normally disconnected from the contact-making parts, means by which the movement of the key for starting the making of the contacts also connects the contact-making parts to said circuit, a receiver-hook, and means by which a descent of said hook disconnects said circuit from the contact-making parts.

11. The combination of two electric circuits over which impulses may be sent, of a calling device provided with one contact-closing device for sending impulses over one circuit and a second contact-closing device for sending an impulse over the other circuit, means for setting the first contact-closing device into operation, a receiver-hook provided with connections for operating the second contact-closing device, and means by which the operation of the second contact-closing device will not send an impulse over the second circuit until after impulses have been sent over the first circuit by the first contact-closing device.

12. The combination with a contact-closing device, a battery, and a normally open connection between said battery and said contact-closing device, a receiver-hook arranged to operate said contact-closing device during its descending movement, and a key arranged to close the connection between said battery and said contact-closing device, when said hook is in an elevated position.

13. The combination with a contact-closing device, a battery, and a normally open connection between said battery and said contact-closing device, of a receiver-hook, a key arranged to close the connection between the battery and the contact-closing device, when said hook is in an elevated position, and means by which a descent of the

hook will first cause an operation of said device and then break its connection to said battery.

14. The combination with two electric circuits over which impulses may be sent, of a separate contact-closing device for each circuit, independently-operative means for causing the contact-closing devices to send impulses over their respective circuits, and means by which the second contact-closing device is inoperative to send an impulse over the second circuit until after the first contact-closing device has been operated to send impulses over the first circuit.

15. The combination with a battery, a contact-making device normally disconnected from said battery, and means for operating said contact-making device, of a telephone-calling device adapted to be operated for the selection of a desired telephone-station, and means by which the operation of said calling device will connect said contact-making device to said battery.

16. The combination with a circuit over which impulses may be sent, of a contact-making device normally disconnected from said circuit, an indicator arranged to be set for the making of any desired number of contacts by said device, a key for connecting said circuit to said device and for starting said device into operation, and a receiver-hook arranged to disconnect said device from said circuit.

17. The combination with one branch of an electrical circuit, and two other branches normally disconnected from the first branch, of a key for connecting the first branch to the

others so as to form two complete circuits, a contact-maker in one circuit for sending impulses thereover, an indicator for determining the number of impulses to be sent by said contact-maker, means by which a movement of said key to connect the first branch to the others will set said contact-maker into operation, a separate contact-maker in the second circuit, a receiver-hook arranged to operate the contact-maker in the second circuit, and means by which upon the hook operating such contact-maker the making of a contact thereby will be followed by said hook breaking the connection between the first branch and the other two branches.

18. The combination with two normally incomplete circuits and a separate contact-maker for each, of an indicator for determining the number of contacts to be made by one contact-maker, a receiver-hook for causing an operation of the second contact-maker, a key for closing said circuits elsewhere than at the points at which said contact-makers operate, means by which a movement of said key to close said circuits will start the first contact-maker into operation, and means by which a descent of said hook to operate the second contact-maker will restore said key to its normal position and break the connections made thereby.

Signed at Chicago, Illinois, this 7th day of June, 1904.

FRANK A. LUNDQUIST.
